UNITED STATES PATENT OFFICE.

THOMAS E. KING, OF STOCKTON, CALIFORNIA.

ROLLER-SKATE.

1,044,187.

Specification of Letters Patent. Patented Nov. 12, 1912.

Application filed August 14, 1911. Serial No. 644,019.

To all whom it may concern:

Be it known that I, THOMAS E. KING, a citizen of the United States, residing at Stockton, in the county of San Joaquin and State of California, have invented a new and useful Roller-Skate, of which the following is a specification.

This invention relates to roller skates and has for its object to provide an improved, substantial and cheap device of this character.

A further object is to provide improved means for changing the alinement of the rollers according to the shifting of the weight of the skater and to afford proper resiliency to overcome the jarring action to which it is susceptible.

With the above ends in view this invention is embodied in certain details of construction which are hereinafter described and pointed out in the appended claims.

The invention is illustrated in the accompanying drawings, in which similar reference characters indicate similar parts, and in which,—

Figure 1 is a side elevation of a roller skate embodying the invention, parts broken away. Fig. 2 is a bottom view thereof, with the toe clamps removed. Fig. 3 is a vertical longitudinal sectional view in detail taken through one end of the skate.

Referring specifically to the drawings, 5 designates a foot plate of suitable design, which is provided with a heel guard 8 at its rear end and suitable toe clamps 9 at the front end thereof. This foot plate is preferably stamped and pressed from sheet metal. To strengthen this foot plate has been provided a casting, preferably of wrought iron, 40 comprising an elongated block 7 and an upper flange 6, which flange is riveted to the bottom of the foot plate 5, the casting extending from the heel portion of the foot plate to the toe portion thereof. The ends 45 of the block 7 are reduced in depth as indicated at 10 and have the lower faces thereof declined outwardly toward the end of the skate. In each end 10 of the block is arranged a vertical hole or socket 11.

50 A vertically arranged stud bolt 21 having the lower head 20 is screwed into each end of the deeper portion of the block 7 and a jam nut 19 on each of the said bolts serves to hold same in position by binding against the said block 7. A carrier 14 is arranged at each end of the skate, each being of L-

shape comprising a vertical arm 13 and a horizontal arm 24. A pintle 12 projects from each of the vertical arms 13 and enters the respective sockets 11 in the reduced ends 10 of the block 7 to form a swivel connection between the carriers and the said block. The axis of each of the pintles 12 and the corresponding socket 11 intersects the axis of the floor, and the pintles 12 are slidable axially in the socket 11. The horizontal arms 24 of the carriers have an integral cup 16 at the outer ends thereof and a sleeve 23 integral therewith intermediate the ends thereof. 70 The cupped ends of the arms 24 are mounted loosely on the respective bolts 21 and normally rest on the heads 20 of the said bolts. An inverted cup is arranged on the upper end of each of the bolts 21, bearing against the jam nuts 19, and a cushion 17 of rubber or other resilient material, cylindrical in form, is disposed between each cup 18 and the cup-shaped end 16 of each of the arms 24. An axle 22 is passed through each of the sleeves 23 of the carriers and on each end thereof is mounted a suitable wheel 15.

The axles being arranged intermediate the ends of the arms 24 of the carriers throw a greater portion of the weight of the skater 85 on the cushion 17, which being resilient obviates the jarring caused by the movement of the skate over the surface of the floor. Upon the weight of the skater shifting to one side or the other, the carriers are swung 90 between the pivotal point of the pintles in the sockets 11, and the loose connection between the cup-shaped end 16 of the horizontal arm allows the wheels to change their alinement accordingly. The action of 95 the cushion is greatly increased and benefited by being disposed between the cup 18 and the cup-shaped end 16 of the horizontal arms of the carriers and the resiliency of the skate is increased by disposing the axles 100 intermediate the ends of the horizontal arms.

When the foot plate 5 is tilted sidewise, the carriers will swing about the axes of the pintles 12, which will cause the cup-shaped portions 16 which loosely engage the bolts 105 21 to move at a greater rate of motion than the lower ends of the bolts, or causing the cup-shaped portions 16 to move laterally and upwardly relative to the bolts as the bolts are swung. It will therefore be noted 110 that when the foot plate is sloped to a proper angle, that the bolts 21 will strike

the cup-shaped portions 16 for the purpose of limiting the tilting movement of the foot plate. The lateral motion of the cup-shaped portions 16 relative to the bolts also causes 5 the cushions 17 to be bowed or twisted in order to impede the tilting movement of the foot plate and in order to retain the wheels in alinement unless the proper pressure is applied to the foot plate to tilt same. It 10 is for this reason that the cup-shaped portions 16 are mounted loosely on the bolts 21, and that the tubular cushions 17 are mounted loosely on the bolts 21 and embedded in the respective cup-shaped portions 16 and 15 the cups 18. As shown in Fig. 3, the diameter of the bolt 21 is smaller than the opening in the cup-shaped portion 16 and the passage through the cushions in order to permit the operation of the devices above 20 described.

Each end of the block 7 and each of the carriers 14 and corresponding parts are of like design and proportions whereby the parts at the two ends of the skate are interchangeable and being similar dispenses with the necessity of having two carriers of different design and construction. The block 25 7 extending from the toe portion of the skate to the heel portion thereof strengthens 30 that portion of the foot plate intermediate the heel and toe which has been found to be the weakest point thereof and which has heretofore caused considerable annoyance in common skates of this character. After a 35 number of trials it has been found that the provision of the block 7 as above described completely eliminates the tendency of the foot plate to warp or break at that portion thereof intermediate the heel and toe.

40 What is claimed is:—

1. In a roller skate, a foot plate, a member depending therefrom, a carrier loosely engaging the said member and having a pivotal and slidale engagement with the foot 45 plate on an axis which intersects the axis of the said member below the floor, wheels carried by the carrier, and a cushion on the said member between the foot plate and the carrier, whereby when the foot plate is tilted 50 sidewise the carrier moves laterally at its

point of engagement with the said member at a greater rate of motion than the said member at that point in order to impede and limit the tilting movement of the foot plate.

2. In a roller skate, a foot plate, a member 55 depending therefrom and having a lower head, an L-shaped carrier having its horizontal arm loosely engaging the said member and having its vertical arm pivotally and slidably engaged to the foot plate on an 60 axis which intersects the axis of the said member below the floor, wheels carried by the carrier, and a tubular cushion disposed between the foot plate and the horizontal arm of the carrier, so that when the foot 65 plate is tilted sidewise the horizontal arm of the carrier moves laterally at its point of engagement with the said member at a greater rate of motion than the said member at that point in order to impede and limit 70 the tilting movement of the foot plate.

3. In a roller skate, a foot plate, a member secured on the bottom of the foot plate and having a socket therein, a bolt screw-threaded into the said member and having a lower 75 head, an inverted cup on the upper end of the bolt, an L-shaped carrier, the vertical arm on the carrier having a pintle engaging slidably in the said socket, the axis of the socket and pintle intersecting the axis of the 80 bolt at a point below the floor, and the horizontal arm of the carrier having a cup-shaped end loosely engaging the bolt, a tubular cushion having the ends thereof embedded in the said cup and cup-shaped end 85 of the horizontal arm, and wheels carried by the said horizontal arm, so that when the foot plate is tilted sidewise the said cup-shaped end moves laterally at a greater rate of motion than the lower end of the bolt in 90 order to impede and limit the tilting movement of the foot plate.

In testimony that I claim the foregoing as my own, I have hereto affixed my signature in the presence of two witnesses.

THOMAS E. KING.
